Int. Cl. D12—05

U.S. Cl. D12—60

FIG. 1

FIG. 6

FIG. 5

FIG. 7

FIG. 1 is a perspective view of a boom section for a cantilevered crane boom showing my new design, the view showing the front, bottom and one side thereof;

FIG. 2 is a side elevational view, on a reduced scale, showing the opposite side thereof;

FIG. 3 is a top plan view thereof on a reduced scale;

FIG. 4 is a bottom plan view thereof on a reduced scale;

FIG. 5 is a front elevational view thereof on an enlarged scale;

FIG. 6 is a rear elevational view thereof on an enlarged scale; and

FIG. 7 is a cross-sectional view thereof on an enlarged scale taken substantially on the line 7-7 of FIG. 2.

I claim:

The ornamental design for a boom section for a cantilevered crane boom, substantially as shown.
